Des. 235,714
Patented July 8, 1975

235,714

RACK FOR TOOTHBRUSHES AND TOILETRIES OR THE LIKE

Harry Lesser, Jr., Clayton, Mo., assignor to Halame Company, St. Louis, Mo.

Filed Nov. 13, 1972, Ser. No. 306,328

Term of patent 7 years

Int. Cl. D6—06

U.S. Cl. D6—94

FIG. 1

FIG. 2

FIG. 3

FIG. 4

FIG. 5

FIG. 6

FIG. 1 is a top plan view of a rack for toothbrushes and toiletries or the like showing my new design.

FIG. 2 is a front view thereof.

FIG. 3 is a back view thereof.

FIG. 4 is a bottom view thereof.

FIG. 5 is an end elevational view from the left hand side of FIG. 1.

FIG. 6 is a side elevational view from the right hand side of FIG. 1.

I claim:

The ornamental design for a rack for toothbrushes and toiletries or the like, as shown.
